OIL BURNER

Charles E. Swallow, Worcester, Mass.

Application March 4, 1939, Serial No. 259,812

5 Claims. (Cl. 158—36)

This invention relates to oil burners and especially to oil burners adapted to burn heavy industrial oil.

Heavy industrial oil frequently contains particles of carbon and other semi-solids which are liable to clog a valve or a burner when set to burn such oil in small quantities, and this makes it difficult to use heavy industrial oil in a burner where the conditions are such that only small quantities of oil are required.

One of the objects of my invention is to provide a novel oil burner which is well adapted to burn efficiently heavy industrial oil in relatively small quantities, and which is so constructed as to provide a free flow of such heavy industrial oil even when the oil is being consumed in the burner in relatively small quantities.

A further object of the invention is to provide a burner of this type which has a gravity feed of oil to the burner and which can be successfully operated with a relatively low air pressure for atomizing the oil at the burner.

Further objects of the invention are to provide a novel burner which is constructed so that the fuel mixture, that is, the mixture of oil and air, can be varied independently of the volume of the mixture, so that when the correct mixture has once been established, the volume of the flame can be increased or decreased without changing the proportions of the mixture.

Further objects of the invention are to improve oil burners in various particulars which will be hereinafter set forth.

In the drawings:

Fig. 1 is a diagrammatic view showing a layout for a group of oil burners to be supplied from a central supply tank;

Fig. 2 is a sectional view showing one of the burners and its supply reservoir;

Fig. 3 is a section on the line 3—3, Fig. 2 with the float valve and oil circulating pipe shown in plan;

Fig. 4 is an end view of the valve for controlling the supply of oil to the reservoir chamber;

Fig. 5 is a section on the line 5—5, Fig. 6;

Fig. 6 is a section through the valve on the line 6—6, Fig. 5.

Referring first to Fig. 2 wherein I have shown one oil burner and its supply reservoir, 1 indicates generally the burner nozzle and 2 indicates the supply reservoir which supplies oil to the burner 1.

The reservoir 2 is formed with an open-topped reservoir chamber 3 containing oil 4 which is

to be supplied to the burner, said chamber 3 being connected to the burner 1 through the supply pipe 5.

The reservoir 2 is a jacketed reservoir, it being provided with a jacket chamber 6 which surrounds the oil-containing chamber 4 and through which heated oil is continually circulated, said jacket chamber having a supply pipe 7 leading thereto at one end of the reservoir and a discharge pipe 8 leading therefrom at the other end of the reservoir. Suitable means, such, for instance, as a pump, presently to be described, are provided to circulate the heated oil through the pipe 7, jacket chamber 6 and pipe 8. As a result, the oil 4 (which may be heavy industrial oil) in the reservoir chamber 3 is kept warm, and thus in a free-flowing condition. The heated oil is supplied to the chamber 3 directly from the jacket chamber 6 through a port formed in the partition wall separating the oil-containing chamber 3 from the jacket chamber 6, and means are provided for maintaining a constant oil level in the chamber 3, such means operating to admit additional oil to the chamber 3 from the jacket chamber 6 when the oil level in the chamber 3 falls, and operating to shut off the supply of oil from the jacket when the oil level in the chamber 4 rises to a predetermined point.

While various means for thus controlling the oil level may be employed, I prefer to use a float valve for this purpose, and that herein shown comprises a valve casing 9 secured to the wall of the oil-containing chamber 3 and provided with an inlet passage or port 10 communicating with the jacket chamber 6 and a discharge passage 11 leading to a discharge pipe 12 through which oil is delivered to the chamber 3. The flow of oil through the port 10 and the discharge passage 11 is controlled by a sliding valve 13 which operates in a valve chamber 14 formed in the casing 9, said valve having a face 15 adapted to seat against a valve seat 16 thereby to close the communication through the ports 10 and 11. This valve is provided with a valve stem 17 which is connected to one arm 18 of an actuating lever 19 that is pivoted to the valve casing by means of a pin 20, said lever carrying at its outer end a float 21. The upper end of the arm 18 of the lever 19 is shown as forked and this fork embraces a collar 22 which is formed with an annular groove to receive the ends 23 of the forked arm 18, said ends 23 being confined between the flanges 24 of said collar 22.

The rising and falling movement of the float 21 will thus shift the valve 13 longitudinally.

In order to provide an oil flow in the form of a solid stream when the valve is only slightly open, said valve member 13 is formed with an extension 25 which fits the duct 10 and which is provided with a V-shaped groove 26 having a progressively decreasing depth from the free end of the extension 25 to the opposite end 10 thereof where it meets the face 15 of the valve.

In Fig. 2, the oil level is shown at its maximum height in the chamber 3 and the valve is closed. When the oil level in the chamber 3 falls and the float 21 moves downwardly, such downward movement will shift the valve 13 to the right, thereby separating the face 15 from the seat 16 and at the same time bringing the small end of the groove 26 into communication with the discharge port 11. There will then be a small flow of oil in the form of a stream passing through the small end of the groove 26, and because the oil is flowing in the form of a solid stream, there is very little likelihood that the passage through the valve will become clogged by any small particles of carbon or other semi-solid matter which is so frequently found in heavy industrial oil.

When the oil level in the reservoir 3 has again risen to the point shown in Fig. 2, the valve will be closed, thereby shutting off further flow of oil.

The oil burner comprises a housing member 21 having an oil duct 28 communicating with the supply pipe 5, said duct leading to an oil discharge tube or nozzle 29 through which the oil is delivered. This housing 21 also contains an air chamber 30 to which air under the desired pressure is supplied through an air pipe 31.

The burner also is formed with an air discharge passage 32 communicating at one end with the air chamber 30 and having its opposite end 33 situated adjacent the delivery end of the oil tube 29 and so positioned that the air which is delivered through the passage 32 will be forced transversely across the discharge end 34 of the oil tube 29, thereby creating a vacuum within said tube which draws oil 4 from the reservoir 3 into the tube 29. The air stream delivered from the orifice or passage 32 not only draws the oil by suction from the reservoir 3 but it also atomizes the oil and thus delivers it in the form of a fine spray.

The passage 32 is controlled by a suitable valve 41 which regulates the amount of air that can pass through the passage. This valve is shown as having a valve stem 42 which is screw-threaded through the valve casing 27 and is provided with a handle 43 by which it may be manipulated. The adjustment of the valve 41 determines the character of the fuel mixture.

The burner 1 is provided with an annular air discharge orifice 35 surrounding the passage 32, and which communicates with the air chamber 30 so that an annular sheet of air will be delivered into the atomized spray of oil for the purpose of properly supporting combustion. This annular air discharge orifice or passage 35 is formed between a cap 36 which is screw-threaded to the housing 21 and a collar 37 which is mounted on the nozzle extension 38 of the housing 21. The collar 37 has a conical exterior and the cap 36 is formed with an opening in its end through which the collar extends, the wall of the opening forming with the collar the air discharge orifice

35. The oil delivery tube or atomizing tube 28 is shown as extending through the collar 37 and is thus carried thereby, the inner end of said tube fitting into a plug 39 that is located in the outer end of the oil passage 28, said plug having a duct 40 therethrough to provide a communication between the duct 28 and the tube 29.

The supply pipe 31 is also provided with a suitable valve 44 to control the supply of air to the air chamber 30.

The burner will be so mounted or supported that the end 34 of the atomizing tube 29 is situated above the normal oil level in the reservoir 3, such level being indicated by the dotted line 45. Since the chamber 3 is an open chamber, the oil 4 therein is subjected to atmospheric pressure only and because the delivery end 34 of the atomizing tube 29 is above the normal oil level, it will be impossible for the burner to overflow when it is not in operation.

The control of the burner is accomplished entirely by controlling the flow of air to the burner and without the necessity of controlling in any way the flow of oil except to see that there is a constant circulation of oil through the jacket chamber 6. The valve 41 serves to control the mixture of air and oil and by means of it, the correct mixture is obtained. The valve 44 serves to control the volume of the mixture which is delivered from the burner and hence the volume or size of the flame. After the correct mixture has once been established by manipulation of the valve 41, then thereafter the operation of the burner may be controlled entirely by manipulating the valve 44. As long as air is being supplied to the air chamber 30, there will be a flow of air through the passage 32 and across the end 34 of the atomizing tube 29, thereby producing a suction at the end of the tube which will cause delivery of the oil therefrom, such oil being atomized by the flow of air.

There will also be a flow of air through the passage 35 sufficient to properly support combustion. The volume of the flame can be varied by manipulating the valve 44 and thus varying the amount of air which is delivered to the burner. The operation of the burner can be stopped by simply closing the valve 44 and shutting off the supply of air, for when this is done, the suction action at the end 34 of the atomizing tube 29 will cease and the oil delivery will stop. Inasmuch as the end 34 of the atomizing tube is above the normal oil level, there will be no continued flow of oil and no possibility of an overflow when the burner is not in operation.

The collar 37 is shown as secured to the extension 38 by means of a set screw 46 and this construction provides means for adjusting the collar, if adjustment is necessary.

I have above described a single burner and its supply reservoir. In Fig. 1 I have illustrated a schematic layout for a group of burners supplied with oil from the same source. In the diagrammatic view of Fig. 1, a plurality of burners 1 are shown, each having its supply reservoir 2, each burner being connected to its reservoir by the pipe connection 5. The jacket chambers of the various supply reservoirs 2 are connected in series by pipes 7. 48 indicates a supply tank containing oil which is to be supplied to the various reservoirs 2, and 49 indicates a pump designed to take oil from said reservoir 48 and force it through the piping system 7 and through the reservoir jacket chambers 6. The inlet of the pump 49 has connected thereto a pipe 58 which

leads nearly to the bottom of the tank 48 as shown at 53, and the discharge port of the pump 49 is connected by a pipe 61 to a heating reservoir 52 and said reservoir is connected to the pipe system 1. Means are provided for heating the oil in the tank 48 and also in reservoir 52. This means may be any suitable heating means, and merely as illustrating one practical heating means, I have shown steam coils 57 and 60, one placed in the supply tank 48 and the other in the reservoir 52. These steam coils are connected by a pipe 54 and may be supplied with steam from any suitable source by means of a pipe 58, 59 being an exhaust pipe.

15 The piping system through which oil is supplied to the jacket chamber 6 is provided with a return pipe 8 leading back to the supply tank 48, thus making a closed circulating system. The pump 49, therefore will operate to circulate the 20 oil through the heater 52 and through the jacket chambers 6 of the various reservoirs, and then back to the supply tank 48, and this oil circulation may continue regardless of whether any burner is in operation or not.

25 With the float valve construction shown, each reservoir chamber 3 will receive oil from its jacket chamber 6, as called for by its burner, for as the oil is withdrawn from any reservoir chamber 3 by the operation of the burner, the corresponding float valve will operate to admit fresh oil to the chamber 3 from the jacket. There is, therefore, no necessity for the manipulation of any valves to control the supply of oil to any burner, this being taken care of automatically 30 by the float valve construction and by the manual manipulation of the air controlling valve 44.

35 55 indicates a back pressure valve in the return pipe 8. 61 indicates a stop member attached to the valve casing and having an aperture through which the valve stem extends, said stop member serving to limit the opening movement of the valve.

The valve is shown as having a guide pin 62 extending therefrom which operates in a groove 45 63 formed in the valve casing, the purpose of this construction being to prevent the valve from turning on its axis and to maintain the groove or duct 26 always in position to register with the discharge passage 11 when the valve is 50 opened.

While I have illustrated herein a selected embodiment of the invention, I do not wish to be limited to the construction shown.

I claim:

55 1. A device of the class described comprising a plurality of jacketed supply reservoirs, each having an oil chamber and a jacket chamber surrounding the oil chamber, means connecting the jacket chambers of the reservoirs in series, 60 means for circulating heated oil through the several jacket chambers successively, each reservoir having in its wall a port providing a communication between its jacket chamber and its oil chamber through which oil is supplied to the

oil chamber directly from the jacket chamber, means controlling each port so as to maintain a constant oil level in each oil chamber, and a burner element connected to and supplied with oil from each oil chamber.

2. An oil burner comprising a supply reservoir presenting an oil-containing chamber surrounded by a jacket chamber, means to maintain continuously a circulation of heated oil through the jacket chamber, there being a port in the supply chamber wall which separates the oil-containing chamber from the jacket chamber, said port providing a communication between said chambers through which oil is delivered directly from the jacket chamber to the oil-containing chamber, means controlling said port so as to maintain a constant oil level in the oil-containing chamber, a burner element, and means to deliver oil from the oil-containing chamber to said burner element.

20 3. An oil burner comprising a supply reservoir presenting an oil-containing chamber surrounded by a jacket chamber, means to maintain continuously a circulation of heated oil through the jacket chamber, there being an opening 25 through the wall separating the jacket chamber and the oil-containing chamber through which oil may flow directly from the jacket chamber to the oil-containing chamber, a float valve in the oil-containing chamber controlling said opening, whereby a constant oil level is maintained within the oil-containing chamber, a burner element, and means to deliver oil from the oil-containing chamber to the burner element.

35 4. An oil burner comprising a supply reservoir having double walls enclosing an oil-containing chamber, said walls forming between them a jacket chamber which surrounds the oil-containing chamber, means to maintain a continuous circulation of heated oil through said jacket chamber, the inner wall which forms a partition between the jacket chamber and the oil-containing chamber having a port therethrough through which oil may flow from the jacket chamber directly to the oil-containing chamber, 40 means controlling said port so as to maintain a constant oil level in the oil-containing chamber, a burner element, and a pipe connection for delivering oil from the oil-containing chamber to said burner.

45 5. An oil burner system comprising a plurality of burners, a plurality of supply reservoirs, one for each burner, each supply reservoir having an open oil-containing chamber and a closed jacket chamber surrounding the oil chamber, means connecting the jacket chambers of the various supply reservoirs in series, means for maintaining a circulation of oil through the several jacket chambers, means providing for the delivery of oil from each jacket chamber directly to the 50 corresponding oil chamber independently, and means providing gravitational delivery of oil from each oil chamber to its burner.

CHARLES E. SWALLOW.
